2 Sheets-Sheet 2

UNITED STATES PATENT OFFICE.

BERNARD W. STRAW, OF MOUNT AIRY, MARYLAND, ASSIGNOR TO STRAW BALLAST DISTRIBUTOR CORPORATION, OF WILMINGTON, DELAWARE, A CORPORATION OF DELAWARE.

BALLAST CAR.

Application filed March 14, 1927. Serial No. 175,339.

This invention relates to a car structure, and more particularly to a car structure of the hopper type.

One of the objects of this invention is to provide a novel car structure adapted for use as a hopper car, or as a ballast carrying and discharging car.

A further object of this invention is to provide a novel hopper and ballast distributing car which is so constructed that it may be employed, at will, to carry and discharge lading, such for example as coal, or to transport and discharge ballast in a predetermined manner, the structural elements permitting this double use being a permanent part of the car structure.

Another object is to provide a railway hopper car embodying novel means whereby said car may be employed to selectively, or simultaneously, discharge ballast to any desired portion, or portions, of a track ballast cross-section.

A still further object is to provide a novel railway car structure for discharging ballast, said car embodying manually operable means for accurately controlling the distribution or discharge of the ballast to a selected portion, or portions, of a track ballast cross-section, whereby manual handling of the ballast may be avoided in part or in whole.

Another object of my invention, generally considered, is the provision of a hopper car formed with the usual discharge door and provided with apertures equipped with doors located in the floor and sides of one or more of said portions of the hopper or hoppers thereof, which doors are preferably of the sliding type and adapted for being opened or closed any desired amount while the car is loaded for accurately distributing ballast or other material therefrom, as needed.

An object of my invention is the provision of a ballast distributing car provided with one or more hoppers extending from the bottom thereof, which hoppers preferably each comprise a sloping bottom wall, side walls and a swinging door adapted to close the main or discharge opening therefrom, said sloping floor being apertured and means being provided for closing or opening said apertures to the desired extent for even-

ly distributing material therethrough, as needed.

Another object of my invention is the provision of a car formed with one or more hoppers extending downwardly from the floor thereof, each hopper having a swinging door adapted to quickly release the lading of the car and provided with apertured side walls, doors being provided for releasing the lading through said apertures at an accurately regulated rate for distributing material to the sides of the car, as needed.

A further object of my invention is the provision of a ballast distributing car formed with a body and one or more hoppers depending therefrom, each hopper having a main opening therein closed by a swinging door for quickly releasing ballast or other material contained in the car, each of said hoppers involving a sloping bottom sheet and side sheets with apertures provided in all of said sheets and sliding doors normally closing said apertures and adapted for being opened to permit a graduated and accurately controlled flow of ballast beneath and to the sides of the car, as desired.

Other objects and advantages of the invention relating to the particular arrangement and combination of the various parts will become apparent as the description proceeds.

Referring to the drawings illustrating my invention, the scope whereof is defined by the appended claims:

Figure 1 is a partial side elevation of a hopper car, particularly showing one of the hoppers depending from the car body.

Figure 2 is a sectional view on the line 2—2 of Figure 1 looking in the direction of the arrows.

Figure 3 is a fragmentary sectional view on the line 3—3 of Figure 2 looking in the direction of the arrows.

Figure 4 is a fragmentary sectional view on the line 4—4 of Figure 2 looking in the direction of the arrows.

Figure 5 is a fragmentary sectional view on the line 5—5 of Figure 1 looking in the direction of the arrows.

Referring to the drawings in detail, like parts being designated by like reference characters, I have illustrated, fragmentarily, a car 1 which is desirably of the hopper

type and provided with one or more hoppers 2 depending from the body 3 thereof. In the embodiment shown, the car is of the type in which a pair of hoppers is provided on each 5 side of the center sills thereof, the hoppers of each pair discharging longitudinally of the car toward each other through apertures 4 adapted to be closed by doors 5, said doors being preferably hinged at their upper ends 10 as indicated at 6 and provided with any desired type of latch 7 pivoted to the side sheet 8 of the hopper and adapted to engage a stiffener or spreader member 9 on the door and held in latched position by means of a 15 locking cam 10. The aforescribed construction is merely that of an ordinary form of hopper car in which my invention to be hereinafter described may be embodied and it is obvious that said invention may be embodied in other types of cars, if desired.

For forming the hoppers 2, inclined bottom plates or slope sheets 11 are provided connecting the sides 8 of the hoppers and extending from the bottom of the main body 25 of the car to the bottom of the opening 4 in the hopper. One or more apertures 12 are provided in each of these floor plates 11, said apertures preferably lying near the lower edge of the bottom sheet. Along the 30 sides of the apertured portions of the sloping plates 11, guide strips 13 are provided preferably connected to said bottom sheets by rivets 14 with the side edges thereof spaced from said bottom sheets by filler 35 strips 15, whereby guiding grooves 16 are provided in which sliding doors 17 are movable for opening and closing the apertures 12. The guide strips 13 and filler strips 15 also serve as reinforcing means for the bottom sheets of the hopper as will be understood.

As a means for moving said sliding doors 17 to release ballast or other material in the car for distribution on the road-bed at a 45 desired rate, operating levers 18 are provided preferably centrally pivoted with respect to the car as by means of a bolt 19 extending through a plate 20 connected at opposite ends to the inner guiding strips 13 and bottom sheets 11 by common rivets 14. For operatively connecting the operating lever 18 to a door 17, a link 21 is desirably provided, connected at one end, to an intermediate portion of the lever by pivot means 55 22, and, at the other end, preferably extending beneath a U-shaped strap 23 connected to the door by means of rivets 24 and pivotally connected with respect to both said strap and door by means of a rivet, bolt or other pivotal means 25. In order to place the pivotal means 22 in double shear for more securely connecting the lever 18 to the link 21, a strap portion 26 is preferably riveted to and extends from the link 60 21, being spaced from said link on the other

side of the operating lever 18, forming a bifurcated end on said link for receiving an intermediate portion of said lever. The rivet or other means 22 then extends through the members 21, 18 and 26 in the order given. 70 In order to hold the link 21 and the connecting lever 18 in proper position with respect to the slope sheet 11, said link and connected portion 26 preferably extend between the sheet 11 and the U-shaped guide 75 members 27.

The foregoing description applies to the construction for the sliding doors 17 disposed adjacent the center sills or longitudinal center line of the car or, if only one 80 opening is provided in each sloping bottom sheet, it applies to the construction of the door and operating mechanism for the same. When, however, as illustrated in Figure 2, a pair of openings 17 are provided in each 85 sloping bottom sheet 11, a similar construction is applicable to the outer doors 17 and operating mechanism therefor except that the operating levers 18^a for said outwardly spaced doors 17 are preferably pivoted as indicated at 19^a to that portion of the bottom sheet between the openings 12 therein and connected to the respective door by a corresponding link 21^a extending under guiding means 27^a and pivotally connected to the 90 door as indicated at 25^a. The pivotal connection between the link 21^a and the lever 18^a is indicated at 22^a.

The aforescribed construction provides for distributing ballast or other material on 100 the road-bed beneath the car and particularly adjacent and between the rails of the track. For distributing such material to the sides of the car and outside of the ties, an opening 28 is preferably provided on the outer side sheet of each of the hoppers 2. These openings 28 are preferably positioned near the doors 5 but spaced therefrom an amount sufficient to allow for the application of the door-latching means 7. As described in connection with the apertures 12, the apertures 28 are desirably likewise provided with sliding doors 29 supported and movable with respect to guiding strips 30 spaced from the side sheet 8 by means of 115 filler strips 31, said guiding and filler strips being preferably connected to the corresponding side sheet 8 by means of rivets 32.

The operating mechanism for the door 29 may correspond with that for the doors 17 120 and involve an operating lever 33 pivotally connected to the upper guiding and reinforcing strip 30 by means of a bolt or other pivotal means 34 and connected to the door by a link 35 pivotally mounted on said door 125 by a rivet or the like 36 extending through the door and U-shaped bearing means 37. The other end of said link 35 is preferably provided with an auxiliary portion 38 forming a bifurcated end on said link embracing 130

an intermediate portion of the lever 33 and pivotally connected thereto by means of a rivet or other pintle 39. For guiding the link 35 and lever 33, a U-shaped member 40 connected to the door 29 by means of rivets or the like 41 is preferably provided.

In order to prevent interference between the levers 18, 18^a and 33, and portions of the hopper as well as interference between the levers 18 and 18^a and, at the same time, provide proper clearance for manually gripping said levers, the free ends of all of said levers are preferably spaced from the corresponding portions of the hopper, as illustrated, the end of the longer lever 18 being spaced approximately twice as far as the end of the lever 18^a is spaced so as to conveniently clear said lever 18^a and prevent pinching of the operator's hand therebetween.

The operation of a car embodying my invention for distributing ballast or other material on the ground or road-bed of a railroad is as follows. Assuming that the car 25 1 is filled with ballast which it is desired to spread evenly over the road-bed for improving the condition thereof, the swinging door 5 is retained shut while the operator walks beside the car while the same is drawn 30 at a slow rate of speed along the track being worked, said operator manipulating the levers 18, 18^a and 33 to distribute ballast at the desired rate of flow adjacent the center of the track, adjacent the rails and beyond 35 the ties, respectively, in accordance with conditions prevailing on the particular piece of track. On account of having the doors 40 slideable rather than swinging as in the case with the door 5, said doors can be closed as well as opened while the car is loaded 45 with ballast so that it is unnecessary to discharge the ballast in a large quantity at one place and the same may be distributed only where needed, thereby obviating the necessity of smoothing off the ballast to any appreciable extent or using a steam shovel or the like for spreading the same after being initially applied to the road-bed. Although I have illustrated a particular type of sliding door for the purpose of releasing the 50 ballast at a graduated rate of flow, it is obvious that I do not wish to be limited to such a showing as other types of doors permitting such graduated release of the ballast 55 from the side and bottom walls or certain of said walls of the hopper may be employed, within the spirit of the invention.

From the foregoing disclosure of my invention, it will be apparent that I have devised a vehicle particularly adapted for use 60 as a ballast distributing car on a railway, which car is adapted to evenly distribute ballast or deposit the same in accurately graduated amount where needed, thereby 65 obviating the old practice of discharging the

ballast in large quantities and then laboriously spreading the same to the desired amount. Although the operation of the sliding doors for a particular hopper by a single operator has been described, it is obvious 70 that an operator may be positioned at each side of the car so as to simultaneously discharge lading from a plurality of transversely spaced hoppers whereby the entire cross section of the road-bed may have ballast 75 applied thereto simultaneously.

Having now described my invention, I claim:

1. A vehicle formed with a hopper comprising a sloping floor and side walls, and 80 provided with a discharge opening, a door closing said opening, the sloping floor of said hopper being formed with an aperture therein and means for gradually opening and closing said aperture while the vehicle 85 is loaded for distributing material therefrom.

2. A vehicle formed with a body for holding granular material, a hopper extending from said body and formed with a sloping 90 floor, side walls and a discharge opening, a door closing said opening, the sloping floor of said hopper being formed with an aperture therein and closure means for said aperture adapted for gradual operation to 95 release said material, as needed, for spreading it beneath the vehicle.

3. A vehicle formed with a hopper comprising a sloping floor, side walls and a door closing a discharge opening therein, a side 100 wall of said hopper being formed with an aperture therein and means for gradually opening and closing said aperture while the vehicle is loaded for distributing material from the same.

4. A vehicle formed with a body and a hopper extending therefrom, said hopper being formed with a sloping floor, side walls and a door closing a discharge opening thereof, a side wall of said hopper being apertured and a door adapted for gradual operation to open and close said aperture and release material, as needed, for spreading it to the side of the vehicle.

5. A vehicle formed with a body and a 115 hopper extending therefrom and having a sloping floor, side walls and a door closing a discharge opening thereof, said floor and side walls being apertured and means adapted for gradual operation to open and close said apertures while the vehicle is loaded and distribute material therethrough, beneath and to the sides of said vehicle.

6. A car formed with a body for holding granular material, a hopper extending from the bottom of said body and formed with a sloping floor, side walls and a door for discharging the load from the body, the sloping floor of said hopper being provided with an aperture therein, a door adapted to close 130

- 1 said aperture and means for operating said door while the car is loaded to gradually release material from the car, as needed, and distribute the same.
- 5 7. A car formed with a body for holding granular material, a hopper extending from the bottom of said body and comprising a sloping floor, side walls and a door for discharging material therefrom, the sides of said hopper being apertured, doors adapted to close said apertures and means for operating said doors to release material from the car, as needed, for spreading at the sides thereof.
- 10 8. A hopper car formed with a door for discharging ballast from a hopper therein, said hopper being formed with a sloping floor provided with an aperture therein, a sliding door adapted to close said aperture and means for operating said door while the car is loaded to gradually distribute ballast from said car.
- 15 9. A hopper car formed with a door for discharging ballast from a hopper therein, said hopper being formed with a side wall provided with an aperture therein, a sliding door for closing said aperture and means for gradually operating said door while the car is loaded for distributing ballast to the side of the car, as needed.
- 20 10. A hopper car provided with a door for discharging ballast from a hopper therein, said hopper comprising a sloping floor provided with an aperture therein, guiding means along the side edges of said aperture, a door slidably mounted in said guiding means, an operating lever pivotally mounted with respect to said hopper, and a link connecting said door with an intermediate portion of said lever, whereby said door may be opened and closed to the desired extent upon manipulating said lever.
- 25 11. A hopper car formed with a door for discharging ballast from a hopper thereof, said hopper comprising an exterior side sheet formed with an aperture therein, guiding means connected to said sheet adjacent the sides of said aperture, a door slidably mounted in said guiding means, an operating lever pivotally connected to said side sheet at one end and adapted to be manually grasped at the other end and a link connecting said door to an intermediate portion of said lever, whereby movement of said lever opens or closes said door to the desired extent.
- 30 12. In a car structure, a hopper having a lading discharge opening and a plurality of ballast discharge openings therein, means for closing said lading discharge opening, and means for closing said ballast discharge openings.
- 35 13. In a car structure, a hopper provided with a lading discharge opening and a ballast discharge opening, pivoted means for closing said lading discharge opening, and slidable means for closing said ballast discharge opening.
- 40 14. In a car structure, a hopper having a lading discharge opening therein and one or more ballast discharging openings therein, means for closing said lading discharge opening, and manually operable means, adapted to be actuated independently of said first named means, for controlling the discharge of ballast through said ballast discharging openings.
- 45 15. In a car structure, a hopper provided with a plurality of openings, one of said openings constituting a lading discharge opening, and another of said openings constituting a ballast discharge opening, means normally closing said lading discharge opening, means for closing said ballast discharge opening, and manually operable means for controlling said last named means to permit ballast to be discharged by gravity through said ballast discharge opening independently of the lading discharge opening.
- 50 16. A combined hopper and ballast car structure comprising a hopper having a plurality of openings therein, one of said openings constituting a lading discharge opening, means normally closing said lading discharge opening, slidable means for closing the remainder of said openings, and manually operable means for moving said slid- able means to and from closed position.

In testimony whereof I affix my signature.
BERNARD W. STRAW.
